UNITED STATES PATENT OFFICE.

WILLIAM CARLILE WALLACE, OF SHEFFIELD, ENGLAND, ASSIGNOR OF ONE-HALF TO JOHN BROWN & COMPANY, LIMITED, OF SHEFFIELD, ENGLAND.

FURNACE FOR WATER-TUBE STEAM-BOILERS.

SPECIFICATION forming part of Letters Patent No. 691,089, dated January 14, 1902.

Application filed March 29, 1901. Serial No. 53,460. (No model.)

To all whom it may concern:

Be it known that I, WILLIAM CARLILE WALLACE, engineer, a subject of the King of Great Britain and Ireland, residing at Atlas Works, 5 Sheffield, in the county of York, England, have invented certain new and useful Improvements in or Connected with the Furnaces of Water-Tube Steam-Boilers; and I do hereby declare the following to be a full, clear, and 10 exact description of the invention, such as will enable others skilled in the art to which it app pertains to make and use the same.

My invention consists in improvements in or connected with water-tube steam-boilers 15 whereby induced draft can be applied to the furnaces of such boilers.

The boilers and furnaces to which my invention can be applied are, for example, such as are known as the "Babcock & Wilcox," the 20 "Belleville," the "Neclause," and the "Stirling" boilers; but its application is not limited to these.

In carrying out this invention means are provided whereby the induced draft is employed so as to effect practically complete 25 combustion of the fuel without the aid of a specially-constructed combustion-chamber, thus increasing the efficiency of the boiler, economizing the use of fuel, and preventing 30 the formation and escape of black smoke. The draft is induced by means of an air-current-inducing device, such as a fan or fans, placed in the uptake or at the base of the chimney or in other convenient position be-

35 tween the boiler and the chimney, and an air-heating device is employed whereby the induced draft of air for combustion is before entering the furnace heated by the escaping hot products from the furnace and then distributed in thin streams over the burning fuel, so as to mix with the products of combustion arising therefrom in such manner as to cause their complete combustion to take place before entering among or between the 40 water-tubes of the boiler. The air-heater may be of any suitable description. For example, it may consist of a collection of tubes in a casing, the waste products of combustion from the furnace to the chimney passing 45 through or around these tubes and the enter-

ing air for supply to the furnace passing in contact with the other surfaces of the tubes, or the air may be wholly or in part heated by passing through narrow spaces between plates with an air space between, and these may be 55 arranged to constitute the sides, ends, and top casings of the boiler or one or more of them. The air thus heated is carried by ducts or 60 passages extending along the sides and back or in other convenient position to a distributing-chamber arranged in any convenient position to allow of connection by suitable ducts or passages with passages formed in the wall or walls of the furnace, (with or without metal 65 linings,) other walls with passages therein being provided in the case of large fire-grates, which walls divide the fire-grate surface at intervals and run the length of the furnace, this wall or these walls having perforated bricks or slits in them by which the heated air escapes above the fuel. Similar passages and 70 slits or perforations may, if desired, also in some kinds of settings be formed in the bridge-walls. Passages may be also provided for 75 conducting the heated air into the ash-pit beneath the grate, the passages for the heated air to above and below the grate being provided with valves for regulating the supply of air to each or either, as desired.

The accompanying drawings illustrate examples of arrangements whereby this invention may be carried into effect; but the invention is not limited to the precise arrangements shown.

Figure 1 of the accompanying drawings is 85 a longitudinal vertical section of a stationary water-tube boiler and furnace provided with improvements according to this invention. Fig. 2 is a front elevation of the same, partly in section; and Fig. 3 is a horizontal section 90 on the line 3 3, Fig. 1. Fig. 4 shows, partly in front elevation and partly in transverse section on the line 4 4, Fig. 5, a marine water-tube boiler of the Babcock & Wilcox type provided with improvements according to 95 this invention, Fig. 5 being a longitudinal section through one of the fire-doors of the furnace shown in Fig. 4.

The same letters of reference are employed to indicate similar parts in all the figures. 100

2

Referring to Figs. 1, 2, and 3, the draft is induced by means of a fan A or fans at the back of the boiler B and furnace C and between the uptake D and the chimney E, as shown. The outlet from the fan A is connected by a pipe or passage F with the chimney E, and the entrance to the said fan is in communication by a passage G with the uptake D. In the said uptake is formed a chamber H, having a group or groups of tubes I, through which the products of combustion from the furnace pass, as shown by full arrows, into the fan and are discharged by the said fan into the chimney. Air is admitted to the chamber H by openings K and caused to pass, as shown by dotted arrows, therethrough in contact with the tubes I, and thence through pipes or passages L, extending along the sides of the furnace, into chambers M, situated behind the fire-bridge N. The air in its passage by impinging against the tubes I becomes heated by the products of combustion passing through the said tubes. It is obvious, however, that the arrangement may be such that the products of combustion may pass in contact with the exteriors of the tubes and the air pass through the said tubes. The chambers M communicate through openings a with the ash-pit O of the furnace and through other openings b with passages c in the main walls P of the fireplace and in hollow walls P', which divide the fire-grate surface at intervals. In the chambers M are arranged valves d, by means of which the openings b can be closed, so as to direct the whole of the heated air into the ash-pit O, or the openings a can be closed, so as to direct the whole of the air into the passages c in the main walls P of the fireplace and in the division-walls P', or the said valve or valves d may be adjusted so as to direct some of the heated air into the ash-pit and some into the said passages c. The division-walls P' may be built of fire-bricks and be lined or not with metal. In the opposite sides of the walls P' are perforations e, through which the heated air passes in streams over the fuel, the action of the fan A being such that while exhausting the products of combustion from the furnace it also induces air-currents through the heating devices and the distributing arrangements M and P' into the furnace, whereby a practically-complete combustion of the gases rising from the fuel is effected before the products pass between the water-tubes of the boiler. If desired, air-passages similar to those in the walls P and P' of the furnace may be provided in the fire-bridge N, so that the heated air can be directed over the fuel from the back as well as from the sides of the furnace, and means may be provided for admitting cold air under the fire-bars in the ordinary manner.

The arrangement of the air-passages will of course be varied according to the construction and arrangement of the water-tube boiler

to which the invention is applied. For example, in Figs. 4 and 5, which show the invention applied to a marine water-tube boiler of the Babcock & Wilcox type, the duct or passage L for conducting the air from the air-heating device H into the furnace extends along both sides of the furnace and communicates with a passage or chamber M at the back of the furnace and also with passages M², extending across the front of the furnace, except where the fire-doors are situated. The heated air passes from the passage L into the furnace through perforations e in the two side walls P and from the passage or chamber M through similar perforations in the back wall M and also through perforations e in baffle-plates P², constituting one wall of the passages M² at the front of the furnace. By this arrangement heated air can be directed into the fireplace above the fuel from the front and back as well as from the sides of the furnace, and thus be distributed over the whole of the fuel. The intermediate walls P' (shown in Figs. 1, 2, and 3) are omitted from the arrangement Figs. 4 and 5, as these intermediate walls are required only in the case of large grate-surfaces and are for the purpose of distributing the heated air more uniformly over the whole of the fuel.

I do not limit myself to the arrangement of the air-heating device in the uptake as hereinbefore described, as it may be varied. For example, a casing for the boiler may be formed of double plates with a space between the plates and an opening or openings for the admission of air to the said space, which air will be heated by the radiated heat from the boiler, and the said space may be in communication with the air-distributing device M, so that the said heated air will be drawn into the furnace by the fan or fans, as in the arrangement illustrated by the drawings.

Having now particularly described and ascertained the nature of this invention and in what manner the same is to be performed, I declare that what I claim is—

1. The combination with a water-tube boiler, having a combustion-chamber or fireplace in which the products of combustion ascend vertically in contact with the water-tubes above said chamber, of a device for heating air, hollow side walls having perforations discharging air horizontally into the fireplace, passages connecting the air-heating device with the said hollow perforated walls, and a fan or fans situated between the furnace and the chimney, by means of which fan or fans the products of combustion are drawn from the furnace and heated air in streams is drawn through the perforations in the hollow side walls to the fireplace, substantially as described.

2. The combination with a water-tube boiler having a combustion-chamber or fireplace in which the products of combustion ascend vertically in contact with the water-tubes

above said chamber, of a device for heating air, perforated walls at the sides and back of the furnace and perforated plates in the front of the fireplace, a duct or passage, in connection with the air-heating device, extending along both sides, the back, and partly across the front of the fireplace and horizontally communicating with the interior of the fireplace through the perforations in the side walls of the furnace and in the plates at the front of

the fireplace, whereby the heated air is distributed horizontally over the fuel from the sides, back, and front of the fireplace, substantially as and for the purpose described.

In testimony whereof I affix my signature ¹⁵ in presence of two witnesses.

WILLIAM CARLILE WALLACE.
